CLAIM

The ornamental design for a grinder attachment for a stand
mixer, as shown and described.

DESCRIPTION

FIG. 1 is a top-front perspective view of a grinder attachment
for a stand mixer according to our design;

FIG. 2 is a bottom-back perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

Broken lines showing portions of the article form no part of
the claimed design.

Dash-dot lines represent bounds of the claimed design and
form no part of the claimed design.

1 Claim, 8 Drawing Sheets
